US0D1113181S

(12) **United States Design Patent** (10) **Patent No.:** **US D1,113,181 S**
(45) **Date of Patent:** **** Feb. 17, 2026**

(54) **COMBINED MARINE VESSEL AND SEATING**

3,671,071 A 6/1972 Evinrude
4,086,676 A 5/1978 Arruza
4,278,289 A 7/1981 Esposito

(71) Applicant: **Brunswick Corporation**, Mettawa, IL (US)

(Continued)

(72) Inventors: **Prasad Dhananjay Deole**, Winter Springs, FL (US); **Matthew P. Klausky**, Port Orange, FL (US); **Paul E. Olvera**, Edgewater, FL (US); **Zachary M. Handziak**, Columbia, TN (US)

(73) Assignee: **Brunswick Corporation**, Mettawa, IL (US)

(**) Term: **15 Years**

(21) Appl. No.: **29/929,034**

(22) Filed: **Feb. 19, 2024**

Related U.S. Application Data

(63) Continuation of application No. 29/797,837, filed on Jul. 2, 2021, now Pat. No. Des. 1,022,491.

CLAIM

The ornamental design for a combined marine vessel and seating as shown and described.

DESCRIPTION

FIG. 1 is a port, stern side perspective view of our new design.

FIG. 2 is a starboard, stern side perspective view of our new design.

FIG. 3 is a starboard, bow side perspective view of our new design.

FIG. 4 is a top view of our new design.

FIG. 5 is a stern side view of our new design.

FIG. 6 is a port side view of our new design; and,

FIG. 7 is a starboard side view of our new design.

The broken lines in the figures illustrate portions of the combined marine vessel and seating that form no part of the claimed design.

The dash-dot-dash lines represent the border of the claimed design.

1 Claim, 6 Drawing Sheets
